17 Claims. (Cl. 315—17)

The present invention relates to cathode-ray apparatus and methods of operating same, and, more particularly to cathode-ray apparatus of high sensibility for indicating transients in the milli-microsecond region.

The oscillographic recording of milli-microsecond transients presents difficult problems not only because of the wide system-bandwidth required but, also, because the writing or recording speeds are very high. As an illustration, the bandwidth requirement may extend at least to one thousand megacycles per second in order to accommodate pulse rise times of the order of a tenth of a milli-microsecond. At the same time, a recording speed of the order of 10" trace widths per second is required in order to produce a readable record for interpretation. Cathode-ray tubes of the traveling-wave deflection type have been developed to afford a long effective deflection-plate length without introducing transit-time distortion, thereby providing high-beam velocities in the deflection region that assist in meeting the wide bandwidth requirements. Unfortunately, however, such tubes have been limited to deflection sensitivities sufficient to resolve signals of the order of a half a volt. There are many applications, of course, that require much higher sensitivities and the problems attendant upon such applications can not be solved with the aid of present-day cathode-ray tubes. While the problem could be approached by developing an amplifier with the required bandwidth and voltage output to drive such cathode-ray tubes, such a development involves considerable complexity. Attention has therefore been concentrated upon improving the sensitivity of the cathode-ray tube system itself through improving the actual electron-optical operation therein.

An object of the present invention, accordingly, is to provide a new and improved cathode-ray apparatus that shall embody improved electron-optical operation, providing vastly increased sensitivity.

A further object is to provide a new and improved method of operating cathode-ray apparatus to provide such markedly increased sensitivity, particularly at the high speeds required in the above-mentioned transient recording systems.

Still another object is to provide novel elements suitable for use in such cathode-ray apparatus.

Other and further objects will be explained hereinafter and will be more particularly pointed out in the appended claims.

In summary, it has been discovered that vastly improved cathode-ray-tube sensibility, as hereinafter defined, can be achieved through the employment of focusing and deflection fields in overlapping space relationship, preferably with substantial coincidence of the central regions of the focusing and deflection fields in the cathode-ray apparatus. The focusing field is adjusted, moreover, to obtain a magnification substantially equal to the ratio of a predetermined minimum resolvable phosphor spot-cross dimension to the cross dimension of the point source of electrons produced in the cathode-ray apparatus. Pre-

2

ferred constructional and operational details are herein-after more fully discussed.

The invention will now be explained in connection with the accompanying drawings,

5 Fig. 1 of which is a schematic diagram of a cathode-ray tube electron-optical system designed in accordance with some of the principles of the present invention; and

10 Fig. 2 is a perspective view of a cathode-ray apparatus embodying the invention in preferred form, with parts being shown broken away to illustrate details of construction.

15 Referring to Fig. 1, a cathode-ray-tube apparatus is shown comprising an electron gun for producing a point source of electrons comprising a cathode 1 from which electrons are emitted, a control-grid electrode 3 having an aperture 5 through which the electrons produced by the cathode 1 are passed in response to appropriate accelerating voltages, and an anode electrode 7 having an aperture 9 through which the accelerated electrons may pass. The electron gun comprising the cathode 1, the control-grid electrode 3 and the anode 7 is, in effect, an immersion-type electron lens in which the electron beam is formed into substantially a point source 2, known as the cross-over point, between the control-grid electrode 3 and the anode 7. The diameter of the point source of electrons at the cross-over point 2 is represented by the symbol d_{co} . Measurements on existing cathode-ray tubes indicate that cross-over diameters d_{co} of the order of 0.001 inch or 20 1 mil are readily obtainable. The electron beam is shown 30 diverging from the cross-over point 2 through the aperture 9 in the anode 7 in response to anode voltage. None of the conventional operating voltages are shown applied to the various electrodes in this schematic diagram but details concerning the necessary values of voltages will be 35 explained hereinafter. The electron beam continues through an aperture 13 in an aperture stop or limiting device 11 and thence into the fields of a main electron-focusing lens, indicated by the concentric dash-line circles 40 17, and an electron-beam deflection apparatus, indicated by a pair of parallel spaced deflection plates 15, finally to 45 impinge upon a phosphor particle 23 on a fluorescent phosphor viewing screen 21. The application of an appropriate deflection voltage to the deflection field-producing means 15 will cause the stream to impinge upon the phosphor particle 23 at any desired point 19 located any 50 predetermined distance d from the center axis O of the screen 21. The angle of deflection θ between the deflected beam and the axis O is proportional to the deflection voltage. The focusing field 17 converges the electrons into a 55 point when the beam strikes the phosphor particle 23 of the screen 21. In the case of a magnetic focusing field 17 of relatively thin dimensions, the magnification produced in the electron-optical system, represented by the symbol M, is substantially equal to the distance Q from the focusing field 17 to the screen 21, divided by the distance P from the cross-over point 2 to the focusing field 17.

60 In systems employing photographic-recording and similar techniques that permit magnification of the cathode-ray-tube display, the pertinent characteristic for measuring the degree of usefulness of the tube is the number of volts required to deflect the electron trace through one trace width. This is the definition of the "sensibility" before referred to. Another term hereinafter employed is the "writing speed," which is defined as the number of 65 trace widths per second. The full scan produced on the cathode-ray-tube fluorescent screen is also measured in terms of trace widths. In the design of optimum sensibility cathode-ray-tube systems, the above factors are all interrelated, and it is necessary to adjust the 70 design parameters to achieve an optimum relationship between sensibility, writing speed and scan.

While the deflection means 15 could be placed any-

where in the electron path between the cathode 1 and the screen 21, if it is disposed between the focusing field 17 and the screen 21, the sensitivity in the operation of the tube will increase as the deflection means is moved back towards the focusing field 17. If, however, the deflection means 15 is disposed between the focusing field 17 and the cathode 1, movement of the deflecting system toward the focusing field 17 will cause successively increasing shifts in the position of the cross-over point 2. The actual deflection d along the screen 21 is determined by this shift in the cross-over point 2 multiplied by the magnification M of the electron-optical system. The greatest shift in position of the cross-over point 2 is achieved when the deflection means 15 is farthest from the cathode 1 or closest to the focusing field 17.

It has been discovered that, for the purposes of the present invention, the optimum position of the deflection means 15, contrary to the position presently utilized in cathode-ray apparatus, is squarely within the central region of the cathode-ray electron-lens or focusing field 17. Desirable results can be obtained in any position of overlapping relationship between the deflection and focusing fields, but, as before indicated, the coincidence of the central regions of the deflection and focusing fields has been found to produce optimum results. If the focusing field 17 is created by a magnetic electron lens, such as a focusing coil, there is no physical limitation in positioning the deflection means 15 in close proximity to the focusing field and, in fact, with the optimum-condition central-region coincidence. With electrostatic focusing fields, however, there is a limitation on how close the deflection means 15 may be located to the focusing field in view of the physical construction of an electrostatic lens.

The first criterion underlying the present invention, accordingly, resides in the substantial overlapping and preferable central-region coincidence of the deflection and focusing fields 15 and 17, as schematically illustrated in Fig. 1. As before indicated, this is the very antithesis of the arrangement of present-day cathode-ray apparatus in which the deflection means and focusing means are considerably spaced apart, and it has been found to produce the sensitivity required to obtain optimum results in high-speed oscillography and recording. In practice, moreover, it has been found that the effective deflection field in the focusing field region should be restricted to less than about ten percent of the total transverse dimension of the focusing field 17 in order to avoid entering the aberrant portions of the focusing field.

With the reflection position thus optimized by its location within the focusing field 17, the problem then is to determine the optimum electron-optical magnification or position of the focusing field or lens 17. When the focusing field 17 is located farthest towards the cathode 1, maximum sensitivity is achieved but only at the expense of increasing the spot size of the electron beam upon the phosphor layer 23 of the screen 21. This is because the magnification M is maximum at such a location of the focusing field. With the focusing field 17 closest to the screen 21, on the other hand, minimum magnification and the smallest electron-beam spot are produced, but with very low sensitivity. Since, for the applications of the cathode-ray apparatus of the present invention, the primary concern is the sensitivity factor, that is, the number of volts required to deflect the electron beam one spot diameter upon the screen 21, it is necessary to determine what the effect of magnification and other parameters may be upon such sensitivity. From theoretical and experimental data, the following relation has been evolved for the sensitivity S_s of the cathode-ray apparatus of Fig. 1:

$$S_s = \frac{2V_b d_{co} S}{L_o^2} (M+1)^2 + \frac{2d_{co} V_b}{1} \sqrt{\frac{L_o v_{sm}}{AV_s^n j}} M$$

where V_b is the electron beam voltage, S is the electron-

beam scan expressed in number of spot widths at the screen, L_o is the length of the cathode-ray tube, l is the length of the deflection means, L_m is the minimum value of light energy emitted per unit area of screen phosphor for film-recording purposes, v_{sm} is the minimum writing speed required, A and n are screen phosphor characteristics, V_s is the screen voltage, j is the current per unit solid angle in the beam, and the remaining terms have the definitions before presented.

From the above equation, it is evident that a reduction and hence an improvement in the sensitivity S_s results directly from a reduction in the magnification M . The lower usable limit of the magnification M , however, will be determined by the screen resolution. If the minimum resolvable spot diameter is represented by d_{sm} , then the magnification M should be adjusted, in accordance with the present invention, to produce a spot of this diameter; that is, such that

$$M = \frac{d_{sm}}{d_{co}}$$

The screen resolution, therefore, imposes the primary limit upon the system performance. Experience with fine-grain phosphors, as used on image converters and the like, indicates that a resolution of at least twenty lines per millimeter can be obtained. This corresponds to a line width of 0.001 inch or 1 mil. Ordinary P-11 type phosphors will resolve about one-half this number of lines. The minimum recordable line width upon the faster photographic films is also of the order of 1 mil. If, accordingly, the value of 1 mil is utilized as the minimum line or spot width resolvable on the phosphor, the focusing lens 17 together with the overlapping deflection means 15 must be moved sufficiently close to the screen to give a magnification M of substantially unity. This is because, as before stated, the cross-over diameter d_{co} can be made of the order of 1 mil, also. It is of course advantageous to have this magnification M as small as possible, since, for a given aperture of focusing field 17, a small magnification will result in the greatest image brightness.

A second novel criterion underlying the present invention, accordingly, is the placing of the focusing field 17 sufficiently close to the screen 21 to obtain a magnification equal substantially to the ratio of the minimum resolvable phosphor spot cross dimension to the cross dimension of the cross-over point 2 of the electron beam.

In Fig. 2, physical structures, schematically illustrated in Fig. 1, are shown in preferred form. In the upper right-hand corner, the electron gun is illustrated as comprising a conventional electron-emitting cathode element 1, a cylindrical control-grid electrode 3 having a central aperture 5, and a first anode 7 having a central aperture 9. Instead of the three-element electron gun 1, 3, 7 of Fig. 1, the electron gun of Fig. 2 includes a fourth anode in the form of a longer hollow cylinder 4. In accordance with a further feature of the present invention, this second anode 4 is employed to decelerate the electron beam beyond the cross-over point 2 to permit the presence of lower beam velocities in the deflection region of the deflection means 15. Again, for purposes of simplicity, the actual leads connecting these electrodes to voltage sources are not illustrated. The cathode 1 may be operated by connection, for example, to a source of voltage of, say, -1400 volts. The control-grid electrode 3 may be operated with a grid-driving voltage of the order of 200 volts, having a cut-off voltage in a range of from -250 volts to -600 volts. The first anode 7 may be connected to a source of voltage ranging from 0 to 2600 volts. The second anode, however, which, as before stated, decelerates the electron beam beyond the cross-over point 2, may be grounded so that it is at a lower voltage than the voltage of the anode 7. In accordance with the present invention, again as contrasted with prior-art cathode-ray tubes, it has been found that the electron-

beam velocities may be lowered without altering the position or size of the crossover point 2 if the lower-voltage anode 4 is disposed immediately adjacent to the high-voltage anode 7. In such a case, the lens effect of the second anode 4 upon the crossover point 2 is minimized so that the cross-over point 2 remains substantially in the same position and of the same size as if the low-voltage second anode 4 were not employed. The advantage has been gained, however, that, without altering the position or size of the cross-over point 2 of the 10 point source of electrons, lower beam velocities are produced in the deflection region, thereby increasing the sensitivity of the deflection system.

The electron-gun assembly is shown supported from the anode cylinder 4 by means of insulated struts 8 within an evacuated glass envelope 10. The cathode 1 may be energized by leads 8', passed through the end seal or press in the envelope 10 itself may be joined by glassing to a Kovar cup 12 which, in turn, connects with a conducting stainless steel or other tubular member 14 having a diameter of, say, one and a half inches. The Kovar cup 12 may be copper-brazed to the tube 14. Disposed within the tube 14 is the limiting aperture plate or stop 11 having a very narrow substantially rectangular aperture 13 the purpose of which will now be explained. While conventional cathode-ray apparatus utilizes circular apertures for accurate alignment with the signal deflection means, in the present invention, the limiting aperture plate 11 is made part of the deflection system assembly 14 and the aperture 13 is made of greater vertical than horizontal dimension. The aperture 13 is aligned to reduce the electron-beam thickness in the direction of signal deflection. This technique permits closer spacing of the signal deflection means 15 while permitting higher total beam current than can be obtained with the usual conventional circular aperture of smaller cross-section. A typical successfully operated aperture of this character had dimensions 0.030 by 0.100 inch.

Instead of mere parallel deflection plates 15, as shown in Fig. 1, it is deemed preferable to minimize the effects of transit-time distortion at low-beam energy by employing a traveling-wave helical member 15, Fig. 2, which propagates the signal along the electron path at the same velocity as the beam. Somewhat similar traveling-wave deflection systems are described, for example, by J. R. Pierce, in Electronics, 1949, vol. 22, page 97. The helical member 15 is designed so that the propagation time of the signal around one turn of the helical winding is made substantially equal to the time of transit of an electron along a distance equal to the winding pitch. The helical member 15, actually comprises a pair of helical windings 15a, wound upon a ceramic form 15b to provide balanced deflection. The dimensions of the windings and the spacing to the wall of the tube 14 are chosen to provide an impedance of approximately 120 ohms for each section thereof. The axial velocity of the signal along the deflection means 15 is equal to the speed of the resulting substantially 1.4 kilovolt electron beam, in the above illustration. The two helices 15a may be substantially three inches long and their separation, which corresponds to the deflection-plate separation, is about 0.120 inch. The signal and electron transit time for that three-inch length of the deflection system is 3.4×10^{-9} seconds. Coaxial deflection-plate lead-in supports 18, 20 are provided for supplying deflection voltage. These lead-in supports may be brazed to the stainless steel or other conducting tubular body 14 and connection may be made to the deflection members by a Kovar wire 20. This type of assembly enables convenient attachment of high-frequency coaxial lead-in connections and also provides a high degree of ruggedness and dimensional accuracy while maintaining a relatively small diameter of tube 14 that greatly eases the magnetic focusing lens requirement.

The magnetic focusing lens is shown in the form of a pair of focusing-coil rings 17 which, in accordance with the present invention, are centrally mounted along the deflection apparatus 15. The deflection rings 17 may be conventional magnetic coil deflectors disposed in series. The object and image distance are then nearly equal to the focal length of each lens. Each lens, moreover, is then working at its designed optimum magnification. Just beyond the signal-deflection system 15 is disposed a pair of timing sweep or scan deflection plates 30. Since high sensitivity is not required for sweep deflection, the electron input and output ends of the sweep plates 30 are rounded, as shown at 32, to eliminate astigmatic effects that occur because of the proximity of the electron beam to the plates. The sweep plate separation may be 0.150 inch and the length may be 0.6 inch. Sweep voltages may be applied by the coaxial lead-in supports 16.

A further feature of the present invention resides in the employment of post-deflection acceleration provided by a high-resistance spiral 22, as of aquadag, deposited inside the insulating tubular screen support 24. The tubular support 24 may be sealed by Kovar-ring seals 34 and 26 to the left-hand end of the tube 14 and to the flat-disc phosphor-screen 21, respectively. A co-axial high-voltage Kovar lead-in member 28 may be provided at the ring 26, the aquadag spiral 22 being connected at its ends between high voltage and ground. A final anode cylinder 36 may surround the member 24. If the high-voltage post acceleration had been effected in a limited region near the screen 21, a strong lens action would have been exerted upon the electron beam that would have markedly reduced the deflection sensitivity. Through applying the post-deflection acceleration along a long high-resistance path 22 distributed between the screen and the deflection means and of actual electrical length far greater than the physical distance from the screen 21 to the deflection means through the utilization of the spiral 22, such focusing or lens action is greatly reduced and minimum loss in sensitivity results. The construction of the present invention, moreover, has further advantages over conventional post-deflection systems in that a single spiral is utilized instead of the prior-art multiplicity or sets of bands for distributing the accelerating potential in the post-deflection region between the deflection means and the screen 21. Such prior-art systems employ, for example, three to five bands for distributing the post-accelerating potential, requiring a multiplicity of lead-in connections and an external voltage divider and still being appreciably subject to the before-mentioned undesirable lens action, all of which difficulties are eliminated in accordance with the present invention.

With the tube constructed as above explained, sensitivities of the order of 0.026 volt per trace width have been obtained which are from 10 to 100 times better than the sensitivities obtainable with the prior-art high-frequency recording cathode-ray-tube systems. A signal scan of 300 trace widths has been used with the system of Fig. 2 with a sweep-plate deflection factor of about 150 volts per inch. The sweep scan has been of the order of 500 trace widths with a writing speed of 10^{11} trace widths per second. The trace width itself has been of the order of 0.0012 inch, and the transit time of the order of 2×10^{-10} seconds. The band width of the device may be of the order of 450 megacycles per second. Through redesign of the helix structure of the deflection mechanism 15, however, the band width may be raised to the 1000 or 2000 megacycle value frequently required, as before explained.

While the invention has been described in connection with a screen 21 having a phosphor layer 23, it is to be understood that the teachings herein disclosed may also be applied to other types of cathode-ray apparatus including those having other types of screens or targets.

75 Modifications will occur to those skilled in the art and

all such are considered to fall within the spirit and scope of the invention, as defined in the appended claims.

What is claimed is:

1. Cathode-ray apparatus having, in combination, an electron gun for producing a point source of electrons, a screen, electron-focusing means disposed to extend only in a region intermediate the source and the screen for producing a field for focusing the point source of electrons upon the screen, and deflection means disposed in close field-overlapping proximity to the focusing means for producing a field for deflecting the focused electrons along the screen, the deflection means being disposed well within and displaced transversely from the focusing means in order to limit the effective transverse dimension of the deflection field to a fraction of the total transverse dimension of the focusing field, thereby to avoid having the deflection field enter the peripheral aberrant portions of the focusing field.

2. Cathode-ray apparatus having, in combination, an electron gun for producing a point source of electrons, a fluorescent phosphor screen having a predetermined minimum resolvable phosphor-spot cross-dimension, electron-focusing means disposed so that the ratio of its separation from the screen to its separation from the point source of electrons is sufficiently small to produce a field for focusing the point source of electrons up the screen as a spot of cross-dimension corresponding substantially to the said minimum resolvable phosphor-spot cross-dimension, and deflection means disposed in overlapping relation with the focusing means for producing a field for deflecting the focused electrons along the screen, the deflection means being disposed well within and displaced transversely from the focusing means in order to limit the effective transverse dimension of the deflection field to a fraction of the total transverse dimension of the focusing field, thereby to avoid having the deflection field enter the peripheral aberrant portions of the focusing field.

3. Cathode-ray apparatus having, in combination, an electron gun for producing a point source of electrons of predetermined cross dimension, a fluorescent phosphor screen having a predetermined minimum resolvable phosphor-spot cross-dimension, electron-focusing means disposed sufficiently close to the screen between the screen and the point source of electrons to provide a field for electron-optical magnification substantially equal to the ratio of the predetermined minimum resolvable phosphor-spot cross-dimension to the point-source predetermined cross dimension, and deflection means disposed with its central region substantially coincident with the central region of the focusing means for providing a field for deflecting the focused electrons along the screen, the deflection means being disposed well within and displaced transversely from the focusing means in order to limit the effective transverse dimension of the deflection field to a fraction of the total transverse dimension of the focusing field, thereby to avoid having the deflection field enter the peripheral aberrant portions of the focusing field.

4. Cathode-ray apparatus as claimed in claim 1 and in which the dimension of the deflection field in a plane transverse to the direction of travel of the electrons is less than substantially ten percent of the corresponding transverse dimension of the focusing means in the region thereof.

5. Cathode-ray apparatus as claimed in claim 2 and in which the dimension of the deflection field in a plane transverse to the direction of travel of the electrons is less than substantially ten percent of the corresponding transverse dimension of the focusing means in the region thereof.

6. Cathode-ray apparatus as claimed in claim 2 and in which a limiting aperture is disposed between the point source of electrons and the deflection means, with the length of the aperture along the direction of deflection of

the electron beam along the screen being greater than the width of the aperture.

7. Cathode-ray apparatus as claimed in claim 6 and in which the said limiting aperture is of substantially rectangular configuration.

8. Cathode-ray apparatus as claimed in claim 2 and in which the electron gun comprises an electron-emitting cathode, a control electrode and a high-voltage apertured anode for converging the electrons from the cathode to form the said point source in the region of the aperture of the high-voltage anode, and in which a lower-voltage electrode through which the electrons may pass is disposed immediately adjacent the high-voltage anode to reduce the electron velocity without substantially altering the position or size of the said point source of electrons.

9. Cathode-ray apparatus as claimed in claim 2 and in which the deflection means comprises helical conductor windings.

10. Cathode-ray apparatus as claimed in claim 9 and in which the helical conductor windings are in the form of two traveling-wave helices wound upon ceramic forms to provide balanced deflection.

11. Cathode-ray apparatus as claimed in claim 2 and in which a high accelerating voltage is applied in the region of the screen, a low-voltage anode is disposed close to the deflection means, and a high resistance path is provided between the screen and the low-voltage anode the length of the path being greater than the distance from the screen to the deflection means in order to reduce focusing action therebetween.

12. Cathode-ray apparatus as claimed in claim 11 and in which the high-resistance path comprises a spiral between the screen and the said low-voltage anode.

13. A method of operating cathode-ray apparatus provided with a phosphor screen having a predetermined minimum resolvable phosphor-spot cross-dimension, that comprises, producing a point source of flowing electrons of predetermined minimal cross dimension, producing a focusing field disposed to extend only in a region intermediate the source and the screen to focus the point source of electrons upon the screen, adjusting the position of the focusing field sufficiently close to the screen to provide electron-optical magnification substantially equal to the ratio of the predetermined minimum resolvable phosphor-spot cross-dimension to the point source predetermined cross-dimension, applying a deflection field in overlapping space relation with the focusing field with substantial coincidence of the central regions of the focusing and deflection fields, and limiting the effective extent, transverse to the electron flow, of the deflection field within the focusing field to a fraction of the corresponding extent of the focusing field.

14. A method of operating cathode-ray apparatus provided with a screen, that comprises, producing a point source of flowing electrons, producing a focusing field disposed to extend only in a region intermediate the source and the screen to focus the point source of electrons upon a predetermined point, applying a deflection field in overlapping space relation with the focusing field to deflect the electrons from the predetermined point to an adjacent predetermined point, and limiting the size of the deflection field transverse to the electron flow to or under substantially ten percent of the size of the focusing field in the region thereof.

15. A method of operating cathode-ray apparatus provided with a phosphor screen having a predetermined minimum resolvable phosphor-spot cross-dimension, that comprises, producing a point source of flowing electrons of predetermined minimal cross dimension, producing a focusing field disposed to extend only in a region intermediate the source and the screen to focus the point source of electrons upon the screen, adjusting the position of the focusing field sufficiently close to the screen to provide electron-optical magnification substantially equal to the ratio of the predetermined minimum resolvable

phosphor-spot cross-dimension to the point source predetermined cross-dimension, applying a deflection field in overlapping space relation with the focusing field, and limiting the size of the deflection field transverse to the electron flow to or under substantially ten percent of the size of the focusing field.

16. Cathode-ray apparatus having, in combination, an electron gun for producing a point source of electrons, a fluorescent phosphor screen having a predetermined minimum resolvable phosphor-spot cross-dimension adjusted to correspond substantially to the minimum recordable line width upon photographic films, and electron-focusing means disposed so that the ratio of its separation from the screen to its separation from the point source of electrons is sufficiently small to focus the point source of electrons upon the screen as a spot of cross-dimension corresponding substantially to the said minimum resolvable phosphor-spot cross-dimension.

17. Cathode-ray apparatus as claimed in claim 2 and in which the said resolvable phosphor-spot cross-dimension corresponds substantially to the minimum recordable line width upon photographic films.
